UNITED STATES PATENT OFFICE

140,300

DESIGN FOR A FLASHLIGHT

Joseph Frank, Forest Hills, N. Y.

Application May 2, 1944, Serial No. 113,437

Term of patent 7 years

(Cl. D48—24)

To all whom it may concern:

Be it known that I, Joseph Frank, a citizen of the United States, residing at Forest Hills, in the county of Queens and State of New York, have invented a new, original, and ornamental Design for a Flashlight, of which the following is a specification, reference being had to the accompanying drawing, forming part thereof.

I claim:

The ornamental design for a flashlight, substantially as shown.

JOSEPH FRANK.
